UNITED STATES PATENT OFFICE

138,726

DESIGN FOR AN ASH TRAY

Aloysius W. Becker, Chicago, Ill.

Application September 22, 1943, Serial No. 111,188

Term of patent 7 years

(Cl. D85—2)

To all whom it may concern:

Be it known that I, Aloysius W. Becker, a citizen of the United States and a resident of Chicago, county of Cook, and States of Illinois, have invented a new, original, and ornamental Design for an Ash Tray, of which the following is a specification, reference being had to the accompanying drawing, forming a part thereof, in which Fig. 1 is a perspective view of an ash tray showing my new design. Fig. 2 is a top view of the same on a scale enlarged over that of Fig. 1; and Fig. 3 is a view in elevation of the ash tray on the scale of Fig. 2.

I claim:

The ornamental design for an ash tray, substantially as shown.

ALOYSIUS W. BECKER.
